Primary Examiner — Ricky Pham(74) *Attorney, Agent, or Firm* — Harness, Dickey & Pierce, P.L.C.(57) **CLAIM**

The ornamental design for culinary ware handle, as shown and described.

DESCRIPTION

FIG. 1 is a perspective view of an example embodiment of culinary ware handle in accordance with our new design;

FIG. 2 is a first side elevation view thereof;

FIG. 3 is a second side elevation view thereof;

FIG. 4 is a front elevation view thereof;

FIG. 5 is a rear elevation view thereof;

FIG. 6 is a top plan view thereof; and,

FIG. 7 is a bottom plan view thereof.

The details shown in broken lines are for illustrative purposes only and form no part of the claimed design.
